UNITED STATES PATENT OFFICE.

FRANKLIN F. ADAMS, OF ERIE, PENNSYLVANIA.

IRONING-TABLE.

SPECIFICATION forming part of Letters Patent No. 299,312, dated May 27, 1884.

Application filed June 18, 1883. (No model.)

To all whom it may concern:

Be it known that I, FRANKLIN F. ADAMS, a citizen of the United States, residing at Erie, in the county of Erie and State of Pennsylvania, have invented certain new and useful Improvements in Ironing-Tables; and I do hereby declare the following to be a full, clear, and exact description of the invention, such as will enable others skilled in the art to which it appertains to make and use the same.

This invention relates to the construction of ironing-tables; and it consists in certain new and useful improvements in the same, as will fully appear from the following description and claim.

The device is illustrated in the accompanying drawings, as follows:

Figure 1 shows the table by perspective view set up and in position for use. Fig. 2 is a plan view of the bottom with the supports folded. Fig. 3 is a side view of the table with the supports folded.

The construction is as follows: The table-top is of the usual and common form. On its under side are two ear-pieces, *a a*, by which it is connected with the supports, and a strip, *a'*, which serves as a rest or abutting point for the trussing-brace. The supports consist of a pair of legs at the butt-end of the top and a truss for supporting the small end of the top. *B B* are the legs, and *C* and *E* form the truss. The small end or nose of the table is supported in such a manner that there are no obstructions below or above to its free passage into a skirt or other garment. The legs *B* and brace *C* are pivotally connected with the top on a rung, *d*, which passes through them and the ear-pieces *a*. The other brace, *E*, of the truss is pivotally attached to the brace *C* on the rung *c*. This brace *E* is provided at its upper end with a miter, *e*, so it will seat against the strip *a'*, and at the other end with a notch, *e'*, which embraces the rung *b* between the legs *B*. The position of the supports when the table is erected and when folded can be clearly seen in the drawings. The brace *E*

can be slipped from back of the cleat *a'* very easily by standing at that end of the table and lifting up a little on the top while the foot is on the rung *c'*. Then by bearing down on the brace *E* the notch *e'* will be disengaged from the rung *b*, and the table can then be folded. The operation of erecting the table is equally simple, and need not be described.

On the sides of the table-top, near the legs *B B*, are pins *f f*, which prevent the legs *B*, when unfolded, going beyond a perpendicular position, but as soon as the brace *E* is adjusted in position the legs are firmly held and the pins *f* receive no strain. They simply allow the legs to be thrown out into proper place and go no farther.

This table, it will be seen, is very simple and very cheap, and it is remarkably strong and firm, and at the same time its small or nose end is wholly free at all times to be entered into a garment.

I am aware that tables having hinged legs, a brace attached to said legs and held in place by brace rods or cords, and a top brace hinged to the under side of the top and its foot resting against the brace attached to the leg *s*, are not new; and this I do not claim, as my device differs from that form in that the top, the legs *B*, and the brace *C* have a common pintle, and the brace *E* is attached at or near its middle to a round on the brace *C*. Therefore

What I claim as new is—

An ironing-table consisting of the top *A*, having cleat *a'* and ears *a*, legs *B*, pivoted to the ears *a*, and having round *b*, brace *C*, pivoted to the ears *a*, and having round *c'*, and a swinging brace, *E*, attached at or near its middle to the round *c*, and having notch *e'* to slip over round *b*, all arranged and combined substantially as described.

In testimony whereof I affix my signature in presence of two witnesses.

F. F. ADAMS.
